UNITED STATES PATENT OFFICE

WILHELM BUSSMANN, OF MUNICH, GERMANY

COMBINED HIGH AND LOW PRESSURE PUMP

Application filed December 29, 1927, Serial No. 243,424, and in Germany January 28, 1927.

The present invention relates to a combined high and low pressure pump and has for an object to provide a device of the character mentioned having automatic means for releasing the low pressure pump as soon as a certain pressure has been attained.

Another important object of the invention resides in the provision of a combined high and low pressure pump working automatically and capable of effectively delivering a pressure of 300 atm. and over.

Other important objects and advantages of the invention will be in part obvious and in part pointed out hereinafter.

In order that the invention and its mode of operation may be readily understood by those skilled in the art, I have in the accompanying drawings, set out the possible embodiments of the invention.

In these drawings:—

Figure 1 is a face elevation of the device on the low pressure pump side with the cover removed;

Figure 2 is a section taken through line III—III of Figure 1.

Figure 3 is a face elevation of the device on the high pressure pump side showing portions in section;

Figure 4 is a diagrammatical representation of my invention with the reversing device attached thereto;

Figure 5 is a section through the pump;

Figure 6 is a detail of a portion of the pump;

Figure 7 illustrates the stopping device used in connection with my invention.

Figure 8 is a front view of the operating valve;

Figure 9 is a side view of the same;

Figure 10 is a vertical section through said valve, and

Figure 11 is a horizontal section thereof.

The low-pressure pump is an ordinary gear-pump, the high-pressure one has a barrel with radial bores. The low-pressure gear-pump, with the two pinions 1 and 2 in casting 3, delivers the liquid coming from the pipeline 4 through the connecting pipe 5 to the high-pressure pump and to the ringlike chamber 6 arranged thereabout, the liquid

filling said high-pressure pump and the chamber 6. But a part of the liquid flows through the valve 7 of the inside ring 8 into the main 9. Another part flows into the bores 11 after having lifted and passed the valves 10. When the plungers 12 are outwardly moved, valves 10 are closed and pressure-valves 13 opened. The liquid then passes through the outlets 14 into the outside ring-chamber 15 flowing therefrom into main 9. A special device to return the plungers 12 against the eccentric 16 is not necessary, the plungers being always brought against the eccentric by the pressure of the liquid entering the bores.

As soon as the pressure in the main has attained a certain value and acts upon valve 7 in such a way, that the pressure developed by the gear-pump 1 and 2 does not suffice to lift this valve 7, the delivery of the high-pressure pump alone is discharged through the outlets 14 and the ring-space 15 into the main.

When pressure falls the valve 7 opens again and the gear-pump 1 and 2 takes part in the delivery to the main 9. With low pressure-values, say between 0 and 52 lb. per sq. in., a very fast filling and in this way a very fast raising of pressure is attained, for the entire delivery Q of the gear-pump is discharged into the main. This delivery is governed by the quantity of liquid entering into the ring-space 6, flowing through valve 7, and by the quantity delivered by the plunger-pump. As soon as the pressure has attained the value of 52 lb. per sq. in. a little increase of the delivery of the gear pump will suffice to cause a rapid increase of pressure, because the whole power developed by the plunger-pump is only employed for raising the pressure of the liquid flowing at the pressure of the gear-pump. The drawings show the two pinions 17 and 18 of the gear-pump. The inlet-port 19 of the gear-pump is arranged on the side and, opposite thereto, is the inlet-port 20 of the high-pressure pump. In the example illustrated on the drawing in Figs. 1 and 2 the low-pressure pump is arranged in front of the high-pressure pump and both pumps are centrally mounted with respect to each other, the shaft 21 of the plunger-

5 pump driving at the same time one of the two pinions. The motion of the plungers 22 of the high-pressure pump is performed by driving them against a ball-bearing 23. This ball-bearing is then mounted on a crank 24 of the shaft 21. The delivery of the low-pressure pump is discharged through the chamber 20 and it passes through the valves 25 to the barrel 26. The pressure then exerted upon 10 the plungers 22 drives the latter against the ball-bearing 23 carried by the crank 24. When the plungers are going down, the delivery will open valves 27 and it will flow through these valves into the ring-space 28, from which the liquid will arrive to the main 29.

15 As long as a determined high pressure, to be controlled, is not attained, the remaining portion of the liquid will lift the check-valve 30 of the ring-space 20 and it will flow into the transverse chamber 31. From this chamber the liquid is then discharged into the main 29. But if the pressure surpasses a certain value, so that the pressure of the delivery of the gear-pump would not be able to 20 overcome the counter-pressure acting upon valve 30, the liquid will flow to the plunger-pump only and it will be discharged by the latter into the main. In this case the delivery of the low-pressure pump will surpass the 25 capacity of the plunger-pump. For this reason the arrangement of a valve to be fixed on the connecting pipe would be advisable (this valve has not been drawn on the drawing), the valve allowing the surplus to discharge into the oil-tank. Fig. 3 shows on section between A and B the high-pressure check-valve. The inlet-valves for the high-pressure pump are shown on section between B and C, the high-pressure plungers on section between C and D and finally the high-pressure outlet valves on section between D and A.

20 From the connecting pipe 5 between the high- and low-pressure pump a tube branches off, which tube may be closed by the valve-cone 33. This valve-cone is acted upon by the adjustable spring 34. From tube 32 a passage 35 leads to a reversing-device and a second passage 37 connects the casing 36 of the spring 34 to the reversing-device. This reversing-device consists of a sleeve, in which the double-plunger 39, 40 reciprocates, the two heads of this plunger being held together by rods. An extension 42 of the rods bears 25 on a spring-plate 43 acted on by an adjustable counter-spring 44. The casing 38 of the reversing-device is provided with an outlet-port 45 discharging into the oil-tank (the whole pump lying in oil). The casing of the reversing-device communicates through a passage 46 with the main 9, so that the pressure of the main acts on the rear-side of the plunger 39. If the pressure in the main 9 surpasses the pressure exerted by spring 44, the two 30 plunger heads 39 and 40 are shifted to cover

port 35 and leave open ports 37 and 45. Further outlet-ports 47 are provided in the valve-disc for the purpose of admitting oil into the casing, when valve 33 is open.

35 As it will be understood from the diagram explaining the working of the pump, if the low-pressure pump force the liquid to the high-pressure pump, the same pressure will to be found in the passages 32, 35, in the space between the double plunger 39, 40 of the reversing-valve 38, in the return-passage 37 and in the casing 36 at the rear of the valve. Valve 33 is completely balanced. If now the pressure in the main 9 rises, say to 35 lb. per sq. in. and the spring 44 of the reversing-valve 38 is adjusted to this very pressure, the double-plunger 39, 40 will overcome the pressure of spring 44 at any further increase of pressure. The double-plunger will recede, covering port 35, while ports 37 and 45 will at the same time be opened. By this means valve 33, which was balanced before, will be relieved on the rear-side. It will open, so that in the connecting-pipe 5 and in the passage 6 a decrease of pressure will immediately 40 follow, which decrease of pressure will cause valve 7 to close at once. Valve 33, which is now constantly relieved on its rear-side, will not allow any pressure higher than 28 lb. per sq. in., spring 34 having been adjusted to 45 this very pressure. The surplus of delivery will now lift valve-cone 33 in the valve-disc and it will discharge through ports 47. However, a large quantity of liquid will still be delivered to the high pressure pump. But, as 50 at rising pressure, a relative small quantity of liquid is required for causing a further increase of pressure, the pump will not be able to work with the added quantity of liquid delivered to the high-pressure pump. Thus, 55 in order to avoid losses due to inner-friction which would occur, when the pump would work in its own liquid, the stroke-volume of the high-pressure plunger is the more reduced, in proportion to the increasing pressure.

60 During the stroke the plungers are driven by eccentric 16 into their outward positions and they are then pushed again towards the eccentric through the pressure of the liquid forced into the bores by the low-pressure pump. By means of a special device, i. e. by means of a cam-disc 48, carrying for each plunger a suitable inclined surface, the back movement of the plungers may be adjusted in such a way, that they are prevented from going all the way back, but more or less play may be left between the eccentric and the adjacent portions of the plunger accordingly to the position of the cam-disc, against which the plungers with their stops 49 strike. In this way a reduction of the stroke is reached or, in other words, the stroke-volume is made smaller.

65 An example of this arrangement, diagram- 130

matically shown in Fig. 4, is reproduced in Figs. 5 to 11. Figs. 5 to 7 represent the stroke-altering device, while Figs. 8 to 11 show the operating valve.

The pump-cover 50 carried a shaft 51 having side-arms 52. These arms 52 engage two extensions 53 of the cam-disc 48, which cam-disc having on the opposite side the inclined planes, above mentioned. Plungers 22 have at their lower-ends 57 right-angled slots for these inclined planes of the cam-disc 48. Dependent upon the position of this cam-disc, the upper extensions 54 of the plungers 22 come earlier or later to strike it. In this way the moving down of the plungers is controlled. If the said extensions come earlier to strike the cam, the stroke-volume is reduced. The latter is increased, if the extensions come later to touch the cam. This shifting of the cam-disc may be either mechanically performed in connection with valve 38, that is to say, with the operating valve 36, or by hand. To this purpose cam-disc 48 is provided with the above extensions 53, which pass through slots 55 of the lower-cover 56, the cover being at the same time the bearing for the shaft 21. The side-arms 52 of the shaft 51 engage the spaces subsisting between two extensions 53. If shaft 51 is rotating, it will turn the cam-disc. In this way the extensions 54 of the plungers 22 would earlier or later strike the cam-disc 48. The operating-valve 36 in Figs. 8-11 has a casing 58, which is piped to the connecting-tube between high- and low-pressure pump by means of a screwed socket 59. The operating-valve has a valve-cone 60, acted on by spring 61, which can be adjusted by screw 62. The change-over passage 63 connects the passage between high- and low-pressure pump 20 with the distribution-passage 64 arranged in the casing 65, placed sideways. The double-plunger 66, 67 moves in the distribution-passage, the one end of said plunger contacting with the spring-plate 68. The adjustable spring 69 acts by means of a nut 70 on the spring-plate, pushing this end of the double-plunger into one of the end-positions. Passage 71 branches off from the main and leads 50 to the opposite end of the double-plunger, so that the pressure, which acts on the plunger, can only shift the same. The spring is then drawn together. Three passages 72, 63 and 73 lead to passage 64. If the spring-pressure 55 does overcome the pressure transmitted from the main, passages 63 and 73 will communicate with each other. Front- and rear-end of valve 60 are acted on by the same pressure-value. The valve will therefore be balanced. 60 But if the pressure deriving from the main does overcome the counter pressure exerted by spring 69, the plunger will be shifted. In this case passages 72 and 73 will communicate with each other, so that the rear-side 55 of the valve 60 will be relieved and the valve

itself be caused to open. The liquid will now flow through ports 74. A vacuum will rise in the pipe-lines between the low-pressure pump and the main 9, the vacuum causing valve 30 to close. Double-plunger 66, 67 will still retain its position and the surplus of the delivery of the low-pressure pump will flow back into the oil tank through the lifted valve-cone 60 and the ports 74.

I claim:

1. A device of the character described comprising a low pressure pump, a high pressure pump receiving the delivery from the low pressure pump, the high pressure pump being provided with a first system of passageways for the admission to said high pressure pump of the delivery from the low pressure pump and with a second system of passageways for the delivery of said high pressure pump, means of communication between the two systems of passageways in said high pressure pump, and a valve for controlling the communication between said systems of passageways.

2. A device of the character described comprising a low pressure pump and a high pressure pump receiving the delivery from the low pressure pump, the high pressure pump being provided with a first system of passageways for the admission to said high pressure pump of the delivery from the low pressure pump and with a second system of passageways for the delivery of said high pressure pump, means of communication between the two systems of passageways in said high pressure pump, a valve for controlling the communication between said system of passageways, and means communicating with the high pressure pump and the low pressure pump for limiting and controlling the value of pressure between said pumps when a pre-determined pressure is obtained.

3. A device of the character described comprising a low pressure pump, a high pressure pump receiving the delivery from the low pressure pump, the high pressure pump being provided with a first system of passageways for the admission to said high pressure pump of the delivery from the low pressure pump and with a second system of passageways for the delivery of the high pressure pump, means of communication between the two systems of passageways in the high pressure pump, a valve for controlling the communication between said systems of passageways, and means communicating with the high pressure pump and the low pressure pump for limiting and controlling the value of pressure between said pumps when a pre-determined pressure is obtained, said means including a reversible piston valve having series of cooperating ports, the valve operating under different pressures to open and close certain of said ports.

4. A device of the character described comprising a low pressure pump, a high pressure

- pump receiving the delivery from the low pressure pump, the high pressure pump being provided with a first system of passageways for the admission of said high pressure pump of the delivery from the low pressure pump and with a second system of passageways for the delivery of said high pressure pump, means of communication between the two systems of passageways in said high pressure pump, a valve for controlling communication between said system of passageways, and means communicating with the high pressure pump and the low pressure pump for limiting and controlling the value of pressure between said pumps when a predetermined pressure is obtained, said means including a piston valve having series of cooperating ports, a spring holding said valve in normal position, said valve adapted to open and close certain of said ports when subjected to a pressure overcoming the counter-pressure of the spring.
5. A device of the character described comprising a low pressure pump, a high pressure pump receiving the delivery from the low pressure pump, said high pressure pump consisting of a body, a plurality of pistons radially mounted in said body, means to actuate said pistons, and being provided with a first system of passageways for the admission to said high pressure pump of the delivery from the low pressure pump and with a second system of passageways for the delivery of said high pressure pump, controlled means of communication between the two systems of passageways in said high pressure pump, and means associated with the pistons of the high pressure pump for regulating the stroke of the pistons.
6. A device of the character described comprising a low pressure pump, a high pressure pump receiving the delivery from the low pressure pump, said high pressure pump consisting of a body, a plurality of pistons radially mounted in said body, means to actuate said pistons and being provided with a first system of passageways for the admission to said high pressure pump of the delivery from the low pressure pump and with a second system of passageways for the delivery of said high pressure pump, control means of communication between the two systems of passageways in said high pressure pump, and means associated with the pistons of the high pressure pump for regulating the stroke of the pistons, said means consisting of an adjustable eccentrically mounted disk provided with a plurality of adjacent inclined surfaces engageable with said pistons.
7. In testimony whereof, I have signed my name to this specification.

WILHELM BUSSMANN.
